UNITED STATES PATENT OFFICE.

HENRY A. ZIOLA, OF CLEVELAND, OHIO, ASSIGNOR, BY MESNE ASSIGNMENTS, TO THE SWARTZBAUGH MANUFACTURING COMPANY, OF TOLEDO, OHIO.

ELECTRIC HEATER.

Application filed February 27, 1922. Serial No. 539,395.

To all whom it may concern:

Be it known that I, HENRY A. ZIOLA, a subject of the Government of Poland, residing at Cleveland, in the county of Cuyahoga, and State of Ohio, have invented certain new and useful Improvements in Electric Heaters, of which the following is a specification.

This invention relates to electric heaters 10 of the type known as "hot plates", comprising a stand on which an electric heating element is supported, the stand having a top upon which cooking vessels can rest while they are being heated.

15 The object of the invention is to provide improvements with respect to various features of the article, such as the posts which hold the heating element in place; the method of securing the porcelain insulator 20 through which the current wires are led to connection with the heating element; the means for assembling the legs, base and top plate of the heater, and in various other particulars as will more fully appear from the following description.

In the accompanying drawings, Fig. 1 is a top plan view of the device. Fig. 2 is a side elevation. Fig. 3 is a vertical cross section. Fig. 4 is a plan of the heating element. 30 Fig. 5 is a detail in section showing the manner of constructing and attaching the legs. Fig. 6 is an enlarged detail of the insulator.

The construction of the device is such 35 that its main parts may be made of pressed sheet metal, which is desirable for reasons of cheapness, these parts being assembled in a novel manner as described below.

In the drawings, 6 indicates a base or bottom plate, the outline of which corresponds to the shape desired, being circular as shown, and this bottom plate has a depending flange 7 extending around its edge. The legs 8 are made of sheet metal, and are 45 mainly convex in horizontal cross section, to give the requisite rigidity, the lower end of each leg being bent under and inwardly to form a foot 9 with a circular boss 10, so that the feet will not mar a table or 50 the like. At each edge each leg has formed thereon an inwardly projecting shoulder 11 which terminates in an upwardly projecting tongue 12, and the bottom plate 6 is supported on these shoulders, the flange 7 thereof fitting in the space between

the leg and the tongues 12 and resting at its lower edge against the shoulders 11. The tongues 12 extend through slots in the plate and the projecting ends are then upset or bent down on the top of the 60 plate 6, as indicated at 13. This fastens the plate and legs together and forms a rigid structure.

At the upper end of each leg it is provided with a pair of horizontal inwardly 65 projecting arms or fingers 14 disposed at opposite sides of an upwardly projecting vertical extension or finger 15, and this extension has a small boss 16 pressed thereon. The fingers 14 and 15 thereby form an angular seat for the support of an asbestos plate 17, which supports the heating element. This plate 17 rests upon the fingers 14 and fits snugly against the fingers 15, being preferably notched at the edge, as indicated at 18, so that the fingers 15 fit within 75 in said notches.

The heating element consists of a coiled wire 19 which is fixed at its opposite ends to binding posts 20 which extend through 80 the asbestos plate 17, and between its ends the coiled wire is bent around posts 21, arranged to form a zig-zag. Each of these posts 21 has a head 22, a groove 23, a base flange 24 and a stem 25, the wire coil being 85 bent around in the groove 23 whereby it is held in place. The flange 24 rests on top of the asbestos plate 17 and the stem 25 extends through the same, and the lower end of the stem is riveted or upset as indicated 90 at 26 over a washer 27. The posts are thereby firmly fixed to the asbestos plate, which serves to prevent radiation of heat downwardly and also forms an insulation.

The top plate is indicated at 28. This 95 is stamped to inverted dish formation, with numerous openings in the top, and the articles to be heated are placed thereon. The depending flange 29 of the top plate has a shoulder 30 which rests on the asbestos plate 17 and holds the same in place, and the flange itself fits closely around the edge of said plate and encloses the upright fingers 15, and a snap joint is formed between the flange of the top plate and said fingers by 100 slitting the flange as indicated at 31, and the metal between the slits is pressed in as indicated at 32 a sufficient distance to snap under the bosses 16 when the top plate is forced down into position, the bars 32 yield- 105 110

ing to permit the bosses to pass. The top plate can be removed by wedging a blade under its edge or otherwise springing the same upwardly to pass the bosses. All the parts are thus assembled and held together without the use of rivets or screws.

The current wires 33 are connected to the binding posts 20 under the asbestos plate, and to a pair of posts 34 mounted on an insulating plug 35 which has holes 36 through which extend the current wires 37 leading from a suitable plug and connected to the posts 34. The insulating plug 35 is set in a hole in the bottom plate 6, and around this hole said plate is provided with several inwardly projecting tongues 38. The block 35 has a groove 39 around the same. Before the parts are assembled, the tongues 38 are bent or set up sufficiently to allow the block to be placed in the hole. Then the tongues 38 are sprung into the groove 39, and the block 35 is then forced in with pressure, causing the tongues to bend back to original position and to project into and engage in the groove 39, whereby the block is fastened in position in the plate. The groove is of such slight depth that the tongues when pressed in firmly engage against the block, and the latter is thereby held without the necessity for other fastening devices.

The invention is not limited to the particular form shown, but various changes may be made within the scope of the following claims.

35 I claim:

1. In an electric heater, a top plate, a bottom plate having a depending flange and adjacent apertures, and legs having upwardly projecting spaced tongues passing through the apertures of said plate and providing a supporting seat for said flange in abutting engagement with the legs, the upper portion of said legs being adapted to interlock with the top plate.

45 2. An electric heater comprising a bottom plate having a depending flange and slits adjacent said flange, legs having shoulders on which said flanges rest and flexible tongues extending through said slits and bent down upon the bottom plate, a heating element supported on the legs above the bottom plate, and a top plate mounted on the legs above the heating element.

3. An electric heater comprising a bottom plate having a depending flange around its edge, sheet metal legs bent to convex cross section and having projecting shoulders at their opposite edges on which the flange of the bottom plate rests, said bottom plate having slits adjacent said flange, and the legs having tongues extending through said slits and bent down upon the bottom plate, a heating element supported on the legs above the bottom plate, and a top plate extending over the heating element.

4. An electric heater comprising legs having horizontal fingers projecting inwardly at their upper ends and vertical fingers projecting upwardly adjacent said fingers, an insulating plate resting on the horizontal fingers and fitting between the vertical fingers, a heating element mounted on the insulating plate, and a top plate having a depending flange fitting around the edge of the insulating plate and having a yielding engagement with the vertical fingers.

5. An electric heater comprising legs having horizontal and vertical fingers at their upper edge, an insulating plate resting upon the horizontal fingers and fitting between the vertical fingers, a heating element mounted on the insulating plate, and a top plate having a shoulder resting upon the insulating plate and a depending flange fitting around the edge of the insulating plate and having a snap engagement with the vertical fingers.

6. An electric heater comprising legs having vertical fingers at their upper ends provided with bosses, an insulating plate supported on said legs and fitting between said fingers, a heating element carried by the insulating plate, and a top plate having a depending flange fitting around the edge of the insulating plate and spring bars engageable under said bosses.

7. In an electric heater, an insulating plate, a plurality of posts mounted thereon, each post being grooved and having a stem extending through the plate, and a resistance wire bent back and forth around said posts and engaged in the grooves thereof.

8. In an electric heater, a plate of insulating material, a plurality of posts mounted thereon, said posts having heads at the top, grooves below said heads, and flanges below the grooves, said flanges resting on the plate, and also having stems extending through the plate and fastened thereunder and a resistance element extending around said posts.

9. In an electric heater the combination with a plate having a hole therein and tongues at the edge of said hole, of an insulating block fitting in the hole and having a groove into which said tongues are pressed to hold the block in position on the plate, said block having openings through the same for electrical conductors.

10. In an electric heater the combination of a plate having a hole through the same and spaced tongues around said hole, the ends of the tongues projecting slightly beyond the edge of the hole, and an insulating block pressed in said hole and having a groove in which said tongues are engaged to hold the block in position.

11. In an electric heater, a top plate, a bottom plate having a depending flange and adjacent apertures, and legs having up-

wardly projecting spaced tongues passing through the apertures of said plate and providing a supporting seat in abutting engagement with the legs for said flange, the lower end of said legs being bent laterally and provided with a circular bearing boss upon its under face.

In testimony whereof, I affix my signature in presence of two witnesses.

HENRY A. ZIOLA.
